UNITED STATES PATENT OFFICE.

WILLIAM D. LOWRY, OF ST. LOUIS, MISSOURI.

CAR-BOLSTER AND DRAFT-RIGGING.

No. 884,596.

Specification of Letters Patent.

Patented April 14, 1908.

Application filed December 19, 1906. Serial No. 348,597.

To all whom it may concern:

Be it known that I, WILLIAM D. LOWRY, a citizen of the United States of America, residing in the city of St. Louis and State of Missouri, have invented certain new and useful Improvements in Car-Bolsters and Draft-Riggings, of which the following is a full, clear, and exact description, reference being had to the accompanying drawings, 10 forming part of this specification.

My invention relates to a combined car body bolster and draft rigging and has for its object to incorporate in a construction of this character a plurality of bolsters connected to each other by a bottom or center bearing plate for the purpose of distributing the load of the car body to better advantage than in the use of a single bolster and also for the purpose of affording stronger arrangement for the connection between the body bolsters and the trucks of the car. 20

Figure I is a top or plan view of my combined multiple bolster and draft rigging. Fig. II is an enlarged view in part a front elevation 25 of the central part of the forward bolster and in part a cross section taken on line II-II, Fig. I, through the draft bar. Fig. III is an enlarged rear elevation of the central portion of the rear bolster. Fig. IV is an enlarged top or plan view of my multiple bolster and draft rigging with the forward bolster shown partly in horizontal section. Fig. V is an enlarged section taken transversely through the multiple bolster and longitudinally 35 through the draft rigging.

Referring first to my multiple bolster, 1 designates the rear bolster which is provided at its lower side with a recess 2 that receives a member to be hereinafter referred to.

40 3 is the forward bolster that is provided with a recess 4 that receives the draft bar as will hereinafter more fully appear. The bolster 3 has integral with its top portion a web 5 preferably hollow, which occupies a vertical and central position in the recess 4, 45 see Figs. IV and V.

6 designates a draft bar loop that is slidably positioned in the bolster recess 4 and the sides of which are provided with inwardly extending lugs 7 that normally occupy positions adjacent to the web 5.

8 are spring blocks that rest against the web 5 and 9 are draft springs interposed between said blocks and the ends of the draft bar loop. The force of the draft or buffing is, 55 in the use of the rigging, delivered to the

web 5 of the forward bolster through the medium of the draft spring that is rearmost relative to the direction of movement of the draft bar.

10 designates a bottom connecting plate or member that unites the rear and forward bolsters. This plate is seated in the recesses in the bolsters and is detachably connected to said bolsters by bolts 11, see Figs. II to IV 60 65 inclusive. The connecting plate is provided with a center bearing 12 adapted to rest upon the truck bolster of a car truck and through which the usual king-bolt is passed. The end of the connecting plate which enters 70 into the recess in the forward bolster 3 serves to retain the draft rigging, previously described, in said recess and centrally located upon the top of this end of the connecting plate is a boss 13 that enters into the lower 75 end of the web 5 forming a part of the forward bolster and serves as a medium for staying the lower end of said web in order that it may more effectually resist the strain, 80 to which it is subjected by the draft rigging.

It will be seen that while the connecting plate 10 serves as a member for uniting the two bolsters herein described and as a member for the reception of the king-bolt and the center bearing between said bolsters, it is 85 detachably connected to the bolsters and may be readily separated therefrom for the purpose of permitting the removal of the draft rigging from the bolster whenever circumstances, such as the necessity for repairs 90 of the draft rigging, necessitate the removal of such rigging from the bolster.

I claim:

1. The combination of a plurality of body bolsters having a king-bolt bearing plate 95 whereby they are connected with each other and one of which has a recess extending transversely thereof and open at the bottom of the bolster, and a draft rigging mounted in said recess, substantially as set forth.

2. The combination of a plurality of body bolsters one of which has a recess extending transversely thereof and open at the bottom of the bolster, a draft rigging mounted in said recess, and a king-bolt bearing plate 105 uniting said bolsters and seated in said recess, substantially as set forth.

3. The combination of a plurality of body bolsters, one of which is provided with a recess for the reception of a draft rigging, a draft rigging in said recess, and a king-bolt bearing plate uniting said bolsters and de- 110

tachably fitted to the bolster in which said draft rigging is located for the purpose of closing the bottom of the recess therein, substantially as set forth.

4. The combination of a plurality of body bolsters, one of which is provided with a recess for the reception of a draft rigging, a draft rigging positioned in said recess, and a king-bolt bearing plate detachably fitted 10 to said bolsters and serving to close the bottom of the recess in which said draft rigging is located, substantially as set forth.

5. The combination of a plurality of bolsters one of which has a recess extending 15 transversely thereof and open at the bottom of the bolster, a draft rigging mounted in said recess, and a connecting plate uniting said bolsters and seated in said recess; and said connecting plate being provided with a 20 center bearing located intermediate of said bolsters, substantially as set forth.

6. The combination of a plurality of body bolsters, one of which is provided with a recess open at the lower side of the bolster 25 for the reception of a draft rigging, and has a web extending into said recess, a draft rigging located in said recess and engaging said web, and a king-bolt bearing plate uniting said bolsters and seated in said 30 recess, substantially as set forth.

7. The combination of a plurality of body bolsters, one of which is provided with a

recess for the reception of a draft rigging and has a web extending into said recess, a draft rigging located in said recess and engaging 35 said web, and a king-bolt bearing plate uniting said bolsters; said king-bolt bearing plate having engagement with said web, substantially as set forth.

8. The combination of a plurality of body 40 bolsters, one of which is provided with a recess for the reception of a draft rigging and has a web extending into said recess, a draft rigging located in said recess and engaging 45 said web, and a connecting plate uniting said bolster; said connecting plate being provided with a boss for engagement with said web, substantially as set forth.

9. The combination of a plurality of body bolsters, one of which is provided with a 50 recess open at the lower side of the bolster for the reception of a draft rigging and has a web extending into said recess, a draft rigging located in said recess and engaging 55 said web, and a connecting plate uniting said bolsters and seated in said recess; said connecting plate being provided with a center bearing located intermediate of said bolsters, substantially as set forth.
